UNITED STATES PATENT OFFICE.

MORTON P. TOTTLE, OF GLYNDON, MARYLAND, ASSIGNEE TO WM. A. TOTTLE & CO. INC.,
OF BALTIMORE, MARYLAND, A CORPORATION OF MARYLAND.

VULCANIZER.

1,189,212.

Specification of Letters Patent. Patented June 27, 1916.

Application filed February 1, 1912. Serial No. 574,749.

To all whom it may concern:

Be it known that I, MORTON P. TOTTLE, a citizen of the United States, residing at Glyndon, in the county of Baltimore, State of Maryland, have invented certain new and useful Improvements in Vulcanizers, of which the following is a specification.

This invention relates to an improved construction of vulcanizer particularly adapted for heating and vulcanizing the rubber cement used to secure together the butt-ends of brush bristles, although the invention may be used for purposes other than that mentioned.

15 The object of the invention is to provide an improved construction of vulcanizer which will accommodate a number of brushes at one time and which may be readily operated to apply pressure and heat to 20 the brush parts at the particular point desired, and to make provision for preventing the heat from injuring the bristles, means being also provided to accommodate brushes of various sizes.

25 The invention is illustrated in the accompanying drawings, wherein,

Figure 1, shows the machine in side elevation. Fig. 2, illustrates the same in end elevation. Fig. 3, is an enlarged vertical sectional detail through one set of clamping and heating tables, and Fig. 4 shows a plan view of a portion of a lower clamping and heating table with the brushes in position thereon.

35 In the drawing the numeral, 1, designates suitable supports to which a frame is rigidly attached,—the frame comprising vertical rods, 2, and, 3; horizontal side bars, 4, and end bars, 5—the side and end bars connecting the lower and upper ends of the 40 rods and form an upright rectangular frame. The upright or vertical bars 2, and, 3, are provided at intervals between their lower and upper ends, with stationary bearing 45 bars, 6, which extend horizontally between and are rigidly secured to said vertical bars. These stationary bearing bars are provided with eyes, 7, at their ends through which the vertical bars extend and a pin, 8, or 50 equivalent device is employed in the present instance to rigidly secure the eyes to the rods.

The bearing bars, 6, each have a central vertical bearing, 9, and a horizontal bearing, 10, at one side of and in a plane be-

low the said center bearing. The center bearing, 9, sustains a short vertical shaft, 11, which latter has a screw-threaded upper end, 12, for a purpose presently to be described, and the lower end of said vertical shaft projects through the said center bearing and carries a worm gear, 13, on its lower end which latter turns in a horizontal plane.

The bearings, 10, sustain horizontal shafts, 14, which latter extend between the upright rods, 2, and, 3, and each end of the said shaft carries a worm, 15, that meshes with and drives the worm gears 13, on the lower ends of vertical shafts 11. A suitable hand wheel, 16, is provided on the end of each shaft, 14, whereby the latter may be turned to effect a revolution of the short vertical shafts, 11, at opposite ends of the horizontal shaft.

The bearing bars, 6, on rods, 2, and those on bars, 3 are so arranged on the vertical rods that a bar on rods, 2, and another on rods, 3, will have position in the same horizontal plane so they may sustain between them a horizontal table, 17. By reference to the cross-sectional view in Fig. 3, it will be seen that these tables, 17, have a flat upper or horizontal surface, 18, and a central circular bore, 19. The exterior walls of 35 said tables are preferably angular and in the present instance horizontal ribs, 20, are provided on opposite exterior sides thereof and a covering of suitable material such as asbestos, 21, is provided on the two vertical 40 sides and bottom of said table whereby to prevent the loss of heat by radiation, but the horizontal upper surface of said table is exposed and is without such covering. By reference to Fig. 3, it will be noted that 45 the asbestos covering along the opposite upper sides of the table is beveled as at, 22,—this being done for a purpose which will presently be explained.

Each vertical rod, 2, and, 3, at the opposite ends and corners of the table, 17, carries a bracket, 23,—one end of which has an eye, 24, which embraces the rod and the other end of which turns upwardly at the side of the table and sustains a horizontal shelf or 100 support, 25. It will thus be seen that each shelf or support, 25, is sustained at its ends by the brackets on the rods at opposite ends of the table and that shelves are provided at both horizontal longitudinal side edges 110

of the table. One edge, 26, of each shelf or support is beveled to correspond substantially with the bevel 22, on the table top so as to form an air gap, 27, between the shelf 5 and table. It will be noted that the upper surface, 18, of table, 17, and the upper surface of the shelves, 25, at opposite sides thereof are flush so that the object to be heated may be laid on the table with one end 10 projected onto the shelf. This construction prevents injury to the bristles that rest on the shelf. At each end, the table, 17, carries a horizontal cross-bar, 28, which is secured in place by means of rivets or other fastenings, 29, and the ends of said bars project laterally at opposite sides of the table surface, 18, and each end has an up-turned bracket or eye, 30, with a set-screw, 31, therein. Gage-frames are provided on the 15 upper surface of the table,—one at each side of the said table and said frames have a bar, 32, that extends substantially throughout the length of the table and each end of the bar is provided with adjusting rods, 33, 20 which are engaged by the eyes, 30, and screws, 31, on the cross-bars, 28. Obviously by loosening screws, 31, the rods, 33, may be moved more or less through the eyes, 30, and the bars, 32, moved toward or from the 25 side edge of the table so that the ferrules, 34, of the brushes which are to be heated may have one end butted against the bars, 32, while the bristles, 35, will project across the gap, 27, and lie on the shelf or support, 25, 30 as shown in Figs. 3 and 4, of the drawings. Above each table, 17, the vertical rods, 2, and, 3, of the frame sustain movable bearing bars, 36, each bar having eyes, 37, at its ends and also having a central bearing lug, 38, with a threaded opening therethrough to 35 receive the threaded end, 12, of the short vertical shafts.

A heating and clamping body, 39, is sustained at its ends between two movable bearing bars, 36, the bars themselves being supported on the vertical shafts, 11, as previously explained and consequently when said shafts are turned the heating and clamping body may be raised or lowered 40 with respect to the table, 17, beneath it. The heating and clamping bodies are substantially the same in construction as the tables,—being provided with a circular bore, 40, and angular exterior walls of which 45 three sides are covered with asbestos or equivalent material and the bottom, 41, of which is left exposed for the heat to radiate therefrom;

It is believed to be obvious from the foregoing description that the ferrule-end of the bristles which have been cemented with rubber may be placed on the top or upper surface, 18, of the table and the heating and clamping body then lowered thereon to 50 rigidly clamp the ferrules onto the table and

that if sufficient heat be passed through the ferrules and cemented bristles that a vulcanization will follow.

The heating of the tables and also the clamping bodies is effected by steam and the 70 means therefor will now be described.

By reference to Fig. 2, of the drawing it will be seen that a steam supply pipe, 42, has a valve, 43, and that a branch pipe, 44, extends vertically from the valve which in 75 the present instance is shown above the machine, down to the lowermost table of the machine.

A supply branch, 45, leads from the pipe, 44, and enters the stationary table, 17, near 80 the top surface and at one end and each branch is provided with a valve, 46. These supply branches, 45, are substantially rigid because the tables to which they lead are stationary and each supply branch communicates with the central bore, 19, of the table 85 so as to supply steam to the latter at one end and near the upper surface.

The return connection from the bores, 19, of the tables is made at the opposite end of 90 the tables and near the bottom,—horizontal pipes, 47, serving to effect this return by tapping into a vertical return pipe, 48. These pipes, 47, and, 48, may also be rigid because the tables from which they extend 95 are stationary. It will thus be understood that in so far as the steam connections with the stationary tables are concerned they may all be substantially rigid, with the exception of course, of the allowance made for expansion and contraction, and the supply pipes entering the tables at one end near the top while the return pipes lead therefrom at the other end near the bottom of said tables. The supply and return pipes for the heating 100 and clamping bodies however must be arranged in such a way as to allow the said bodies to have a vertical movement and these pipes will now be described.

By reference to Fig. 1, it will be seen that 110 a branch pipe, 49, extends laterally from a union, 50, at the upper end of supply pipe, 44, and said branch, 49, extends in substantially a horizontal direction and in a plane above the upper side bars, 4, of the frame. 115 At the extreme end the pipe, 49, has connection with a header, 51, and pipes, 52, 53, and, 54, respectively extend in an inclined direction from the header, 51, and in a general direction back toward the vertical supply pipe, 44, as best seen in Fig. 1.

From the lower end of pipe, 52, there is a depending pipe 55, in which a valve, 56, is located and the lower end of said depending pipe turns laterally and enters the top heating and clamping body near the upper side and one end of the latter. In the same manner pipe, 53, carries a depending pipe, 57, in which a valve, 58, is located and this pipe is of greater length than pipe, 55, and ex- 120 125 130

tends down to and enters the intermediate heating and clamping body also near the upper side and at one end. The pipe, 54, also has a depending pipe connection, 59, which is of greater length than either of the pipes, 55, and, 57, and said pipe, 59, also has a valve, 60, therein and its lower end enters the upper portion of the lowermost heating and clamping body near one end.

19 From the foregoing explanation it will be seen that the three heating and clamping bodies are heated by steam that is directed or conveyed thereto through the pipes, 55, 57, and, 59, and that each of these pipes is unsupported between its point of connection with its heating and clamping body and the free end of one or the other of inclined pipes, 52, 53, or 54, which latter may be sprung because of their length without affecting the 20 joint between them and the header, 51. The springing of these pipes only becomes necessary when the clamping body to which they are connected at their lower ends is moved vertically to clamp or free a series of 25 brushes.

The return steam connections from the same clamping bodies is also effected by means of pipes, 61, 62, and, 63, which are provided with valves, 64, 65, and, 66, respectively,—the pipe, 61, being the longest and leading from the lower portion of the uppermost body down to an inclined pipe, 67; the pipe, 62, being the next in length and extending down to an inclined pipe, 68, and pipe, 63, being the shortest and connecting at its lower end with an inclined pipe, 69, as shown in Fig. 2. The lower ends of inclined pipes, 67, 68, and, 69, all connect with a header 70, and from the latter a branch pipe, 71, leads to and connects with a return steam pipe, 72.

From the foregoing explanation it will be seen that each clamping body has a return pipe that is practically unsupported except 45 at the point where it is attached to said body, consequently when the body is moved vertically said return pipe will yield or spring

sufficiently to accommodate itself to such movement of the body.

Having thus described my invention what 50 I claim and desire to secure by Letters Patent is,—

1. A vulcanizer for securing bristles in the bodies or ferrules of brushes, having in combination a table, provided with a circular 55 hollow center and a flat-top surface to support the brush-bodies or ferrules; a flat-top shelf alongside of said table-top and in a horizontal plane flush with the said table-top to support the brush-bristles, and the adjoining edges of said table and shelf being beveled and the beveled edges separated by a gap-space 27, whereby the point of joinder of the brush-ferrules resting on the table-top and the said brush-bristles resting on 60 the shelf-top while being vulcanized, may have position coincident with the said beveled gap-space and thereby prevent heat applied to the bodies or ferrules from injuring the bristles.

2. In a vulcanizer the combination with four vertical guide rods, of a plurality of hollow bodies arranged in pairs and each having an insulating covering which partly incloses it on the exterior but leaves a portion thereof bare and the bare portion of the adjacent bodies confronting each other; two gages interposed between the bared portions of the adjacent bodies; means at one side of the bodies to adjust one gage on the 75 bared portion; means at the opposite side of the bodies to adjust the other gage on the bared portion of a body; means for supplying steam to said bodies and means for moving one of a pair of bodies on the guide rods 80 with respect to the other to vary the space between the bared portions.

In testimony whereof I affix my signature in presence of two witnesses.

MORTON P. TOTTLE.
